UNITED STATES PATENT OFFICE.

WALTER WHITTEN, OF SCHENECTADY, NEW YORK.

ENGINE VALVE.

Application filed February 11, 1922. Serial No. 535,715.

To all whom it may concern:

Be it known that I, WALTER WHITTEN, a citizen of the United States, and a resident of Schenectady, in the county of Schenectady and State of New York, have invented a new and Improved Engine Valve, of which the following is a description.

My invention relates to engine valves either internal combustion engines, locomotives, or other types of engines for controlling the motive fluid to and from multiple cylinders.

The invention will be described in connection with the embodiment of the invention in a valve for internal combustion engines and arranged to function by rotary movement.

The general object of the invention is to provide a novel engine valve of the indicated type improved in various particulars with the result that valve grinding of an internal combustion engine for example is made unnecessary and whereby the motive fluid will be warmed before entering the ignition chamber.

A more specific object of the invention is to provide an embodiment of the invention simple in construction involving a small number of parts.

The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a longitudinal section of a valve embodying my invention, the irregular line of the section being indicated by the line 1—1, Figure 3;

Figures 2, 3, 4 and 5 are cross sections respectively on the lines 2—2, 3—3, 4—4 and 5—5 of Figure 1;

Figure 6 is a view similar to Figure 1 but illustrating the valve in a different position;

Figure 7 is a cross section on the line 7—7, Figure 6;

Figure 8 is a detail in cross section illustrating a modified arrangement of the casing for taking up wear;

Figure 9 is a cross section showing a further modification of the casing designed to take up wear.

In carrying out my invention in accord-

ance with the illustrated example, a valve casing 10 is provided, here shown as cylindrical and having ports 11, 11^a communicating in this instance with cylinders 12, 12^a shown in part, the valve arrangement shown being designed for a two-cylinder internal combustion engine. It will be obvious that any number of cylinders may be employed.

Within the cylindrical valve casing 10 is a rotary valve 13, the one reduced end 14 having a bearing in the head 10^a of the casing and being tubular for the flow of the motive fluid and indicated here as constituting a fluid inlet. The opposite end of the valve 13 is reduced as at 14^a and turns in the head 10^b of the casing 10. At a side of the casing near one end is a discharge 15, it being evident that the inlet and discharge may be reversed.

From the inlet end 14 the motive fluid, or in the case of a gas engine, the fuel, passes laterally from the ports 16 to a chamber 18 in the valve 13 at one end. From the chamber 18 the fluid passes longitudinally through the body of the valve, there being formed for the purpose a plurality of small passages 17 which communicate with a chamber 18^a at the opposite end of the valve 13 and from the chamber 18^a, the fuel flows into longitudinal passages 19, the fuel thus passing lengthwise through the valve in one direction and returning through the passages 19. The passages 19 communicate with ports 20 and 21 adapted to intermittently be brought alternately into register with the ports 11 and 11^a and therefore in communication with the respective cylinders 12, 12^a. In the valve 13, 180° from the ports 20, 20^a are lateral ports 21, 21^a, the ports 20, 20^a being for the live fluid and the ports 21, 21^a for the exhaust. The ports 21 communicate with the hollow interior 22 of the valve and then outward through ports 23 in the reduced end 14^a of the valve and into a chamber 24 at that end of the valve opposite the inlet 14. From the chamber 24 lead longitudinal passages 25 through the valve to a chamber 26 in the casing 10 at the inlet end, said chamber 26 communicating with the exhaust outlet 15.

With the described arrangement as the valve is given movement the inlet port 20 and exhaust port 21 will alternately register with the cylinder 12 while the live port 20^a

and the exhaust port 21^a will alternately register with the port 11^a to establish communication with the cylinder 12^a. In Figure 1 the valve is in a position for the cylinder 12 to exhaust through port 21 and central chamber 22 through ports 23, chamber 24, passages 25, and chamber 26 to the exhaust 15. A movement of the valve 13 from the position shown in Figure 1 to the position shown in Figure 6 will cut off the port 11 and cylinder 12 from connection with the exhaust port 21 and also will cut off communication between said cylinder 12 and the inlet port 20. While the cylinder 12 is thus cut off after exhausting, the cylinder 12^a will be brought into communication with the port 21^a and exhaust chamber 22 and therefore with the ports 23, chamber 24, passages 25, chamber 26 and exhaust 15. A further turn of the valve will bring the inlet port 20 into communication with the cylinder 12 and further movement will eventually bring the inlet 20^a into communication with the cylinder 12^a. The passing of the exhaust forward and back longitudinally of the valve as described gives a muffling effect in addition to utilizing the exhaust to heat the incoming fluid.

The numeral 31 indicates a pinion to constitute one means for giving movement to the valve 13 and the numeral 32 indicates the inlet pipe coaxial with the reduced end 14 of the valve 13.

In Figure 8 I have indicated the adjacent portions of a casing 10^e split longitudinally, there being interposed a triangular piece 27 between the meeting edges to permit of taking up slack by means of a bolt 29 and nut 30, the bolt passing through lugs 28 adjacent the respective edge portions of the casing 10.

The head 18^e of chambers 18, 18^a may be detachably secured by any suitable means such as bolts 33.

In Figure 9 a wedge piece 27^a is employed, similar to the piece 27 except that it has a tapered edge portion, the remaining portion having approximately parallel sides, the casing being indicated by the letter 10^a.

It will be noted that the passages, 17, 19 and 25, extend at both ends through the valve to present open ends accessible for a thorough cleaning of the passages when the heads 18^e are removed.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A rotary valve having a central bore, said valve outward from said bore having

longitudinal fluid inlet passages and having also longitudinal exhaust passages outward of said bore and parallel with said first-mentioned longitudinal passages to give up heat from the exhaust products to the incoming fluid, said longitudinal exhaust passages extending through the valve to present open ends in communication at one end with said bore and at the opposite end with the exhaust outlet, the valve furthermore having lateral ports to communicate with cylinders, said ports adapted to communicate respectively with the said inlet passages and with the central bore of the valve.

2. In a valve, a casing having an inlet and an exhaust, and a valve in said casing having ports adapted to communicate with the ports of a plurality of cylinders, the valve furthermore having passages leading longitudinally through the same from end to end thereof, and return passages, as well as live ports communicating with the return passages, the valve furthermore having lateral exhaust ports and a longitudinal exhaust passage leading to an end of the valve, and exhaust passages leading from said end through the valve to the opposite end communicating with the first-mentioned exhaust passages and with the exhaust of the casing, and means to give movement to the valve to alternately register the respective live ports and exhaust ports with the respective cylinders.

3. A valve of the class described including a casing having ports adapted to communicate with the ports of a plurality of cylinders, said casing having an inlet and a discharge, a valve in said casing having a plurality of fluid-heating passages extending longitudinally through the valve from the inlet end to the opposite end, said valve having chambers at the inlet and outlet ends communicating with said heating passages and having return passages from the chamber opposite the inlet, the valve having live ports communicating with said return passages and adapted to alternately connect the cylinders with the ports of the casing and said valve having exhaust ports adapted to intermittently register with first-mentioned ports of the casing, there being an axial exhaust passage in the valve and a chamber at one end of the casing with which said axial exhaust passage communicates, and longitudinal exhaust passages from the last-mentioned chamber to the opposite end of the valve and communicating with the exhaust of the casing.

4. A valve of the class described including a casing having ports adapted to communicate with the ports of the cylinders of an engine, and a valve in said casing, said valve having live ports and having passages adapted to communicate with said ports of the casing, the valve furthermore having

exhaust passages running back and forth longitudinally of the valve to direct the exhaust forward and back longitudinally in the valve to give a muffling effect.

5. A valve of the class described including a casing having inlet and exhaust ports adapted to communicate with an engine for supplying motive fluid and for exhausting

the same, a valve in said casing having ports and having passages extending forward and back longitudinally through the valve and communicating with the said ports of the valve; together with detachable heads on the valve at the ends of said passages.

WALTER WHITTEN.
